DELIVERY CABINET FOR MILK BOTTLES

Raymond R. Taylor, Darlington, Md., assignor, by mesne assignments, of one-fourth to Melvin P. Johnson and one-fourth to Edwin H. W. Harlan, both of Bel Air, Md.

Application May 5, 1934, Serial No. 724,226

8 Claims. (Cl. 232—41)

This invention relates to a door cabinet for milk bottles and proposes to construct a unit adapted to be set in an aperture cut in a wall or door panel and of that type which permits the milk man to put a bottle in from the front, and housewife to take it out from the rear without the necessity of opening the door.

Cabinets for milk bottles, of the class above indicated customarily include a casing set half inside and half outside the door panel and having opposite openings for the respective insertion and removal of the milk bottle, the outer opening being closed by a cabinet door which the milk man opens to gain access to the cabinet. Such a construction would produce a through opening into the house when the cabinet door is open, which has its objections, to remove which a revolvable drum is generally provided within the cabinet having an opening on one side only, which may be oriented so as alternately to align with the outside or inside opening of the cabinet according to whether the milk bottle is to be placed within or taken out of the cabinet.

One of the objects of the invention is the provision in a cabinet as above described of a spring-rotated drum normally biased to a position in which its opening registers with the inside opening of the cabinet and connected to the door so that when the latter is opened the drum is rotated to a position in which the milk bottle may be inserted from the outside, and when the door is released it automatically closes responsive to the rotation of the drum to its original position.

Another object of the invention is the provision of latching means responsive to the weight of a bottle placed in said drum in upright position, but inert to the weight of the bottle when the latter is placed in the cabinet in inverted position whereby the cabinet door automatically locks in closed position when a full bottle is placed within the cabinet, but remains unlocked when an empty bottle is placed therein in inverted position, so that the milk man can open the cabinet door and remove the empty bottle.

Other objects of the invention will appear as the following description of a preferred and practical embodiment thereof proceeds.

In the drawings which accompany and form a part of the following specification, the same characters of reference have been employed to designate identical parts:

Figure 1 is a perspective view of a portion of a door showing the outside aspect of the milk bottle cabinet with the door closed;

Figure 2 is a similar view from the inside of the

door panel showing the bottle in inverted position;

Figure 3 is a vertical section through the cabinet showing the parts in locked relation;

Figure 4 is a cross section taken along the line 4—4 of Figure 3;

Figure 5 is a cross section taken along the line 5—5 of Figure 3;

Figure 6 is a cross section through the lower part of the cabinet showing the neck of the inverted bottle;

Figure 7 is a cross section taken along the line 7—7 of Figure 3; and

Figure 8 is a vertical section taken along the line 8—8 of Figure 7.

Referring now in detail to the several figures, the numeral 1 represents a frame adapted to be suitably secured to the marginal portions of a door panel or other similar structure surrounding an aperture or hole cut in the door panel for the purpose of installing the device of the invention.

The frame may be of any desired construction, but is here shown as a flange made integral with a cylindrical casing 2. When the frame is in place the casing extends partly inside and partly outside of the door. The casing 2 has openings 3 and 4 in the inner and outer sides thereof, each of which is sufficiently extensive to permit the insertion or removal of a milk bottle. The outer opening 4 is closed by a door 5 preferably of cylindrical curvature corresponding to that of the casing 2.

A hollow drum 6 is mounted within the casing 2 for rotation about a vertical axis by suitable means such as the journals 7 and 8, seated in suitable bearings 9 and 10.

The drum 6 has a single opening 11 on one side and the drum is designed to rotate to either of two operative positions, in one of which the opening 11 registers with the outer opening 4 and in the other of which it registers with the opening 3. When the openings 11 and 3 are in registry passage through the opening 4 is occluded by the imperforate side of the drum 6 even though the door 5 should be open, and when the drum 6 is in its opposite position, that is to say, with its imperforate side toward the opening 3, there is no through passage from the door 5 into the house.

In the preferred form of the invention, a spiral spring 12 freely surrounds the journal 8, being fixed at one end to the underneath surface of the bottom of the drum 6 and at its other end to the adjacent face of the bottom of the casing 55

2. This spring biases the drum 6 to a normal repose position in which the opening 11 in said drum registers with the opening 3 on the inside of the casing 2. The door 5 is connected to the drum 6 by a flexible element or cable 13 which winds upon the upper portion of said drum under the bias of the spring 12, drawing the door 5 closed simultaneously with the turning of the drum to a position in which access may be had 10 thereinto from the house side of the device.

10 The cable 13 is of such length as to act as a stop when the drum registers its closed position, bringing said drum to a standstill when it is in registry with the opening 3. When the door 5 is 15 opened, the cable 13 rotates the drum in a reverse direction against the tension of the spring. When the door has reached its wide open position, it abuts against the frame 1 as shown in Figure 6, being thus stopped when the opening 11 in the 20 drum is in registry with the outer opening 3 of the casing 2.

25 The operation of the device up to the present point in the description is as follows: The milk man opens the door 5 bringing the drum to a position in which a bottle of milk can be inserted through the registering openings 3 and 11. He then lets go the door and the spring 12 automatically closes the door and at the same time rotates the drum to the reverse position shown 30 in Figure 6 in which the openings 11 and 3 register and the housewife can take the milk bottle out.

35 It is highly desirable that when a full milk bottle is in the cabinet the door 5 be locked so that the bottle may not be stolen and is equally important that the door be unlocked when the milk man comes. This selective locking function is accomplished by the following mechanism. On the bottom of the casing 2 is an upstanding keeper 40 14, preferably resilient. A reciprocable bolt 15 extends downwardly through the bottom of the drum 6 adapted to be extended into the path of the keeper 14, but normally maintained in out drawn position with respect to said keeper by 45 a spring 16 surrounding the upper part of said bolt and confined beneath the head 17 thereof. The bolt is overlain by a hinged plate 18, the weight of which the spring is able to sustain when the plate is unloaded. When the milk 50 bottle is inserted within the drum 6 with its weight resting upon the plate 18, the latter depresses the bolt 15 in the path of the keeper 14. Then when the milk man lets go of the door 5, permitting the automatic swinging of the drum 55 under the urge of the spring 12, it swings in the direction indicated by the arrow in Figure 8, the bolt 15 under the weight of the bottle depressing the keeper 14 until the bolt has gone past it, the keeper snapping up into the position shown in 60 Figure 8 and preventing reverse rotation of the drum 6. The position of parts as shown in Figure 8 is reached just when the door 5 has become fully closed and since the door is connected by the cable 13 to the drum 6 and the latter cannot 65 rotate by virtue of being locked, the door 5 cannot be opened.

70 In order to prevent the bolt being pressed down into contact with the bottom of the casing 2 in which position it would act as a brake in retarding the rotative function imparted by the spring 12, a stop 19 is provided upon which the plate 18 rests when the bolt is in locking position, keeping the lower end of the bolt out of contact with the bottom of the casing.

75 When the milk bottle is removed the plate 18

and the bolt 15 spring upwardly under the tension of the spring 16 raising the end of the bolt above the keeper 14 so that the drum 6 is now unlocked. When the housewife returns the empty bottle to the cabinet, she inverts it as 5 shown in Figures 2 and 6. It will be observed that the plate 18 is so shaped and positioned as to leave room for the bottle without being contacted by it. Therefore it will not be depressed and the cabinet will remain unlocked so that the milk man 10 can open the door and remove the empty bottle.

15 While I have in the above disclosure described what I believe to be a preferred and practical embodiment of the invention, it will be understood that the details of construction as shown and described are merely suggestive to those skilled in the art of other equivalent constructions in which the concept of the invention can be carried out.

20 What I claim is:

1. Delivery cabinet for milk bottles comprising a casing having inner and outer openings on opposite sides and adapted to be set in an aperture in a door in a plane intermediate said openings, a rotatable drum in said casing having an 25 opening in one side registrable with either of the openings in said casing, a door co-operating with the outer opening, a connection between said door and drum closing said door through rotation of said drum to a position with its opening in registry with the inner opening of said casing, and a spring for rotating said drum, normally biasing said door to its closed position.

2. Delivery cabinet as claimed in claim 1, including locking means carried by said drum responsive to the weight of a milk bottle within said drum and in operative engagement with said locking means, for locking said door when the latter has reached its closed position in the rotation of said drum.

3. Delivery cabinet as claimed in claim 1, including normally released locking means carried by said drum responsive to the weight of a milk bottle placed within said drum and in operative engagement with said locking means for locking said door when the latter has reached its closed position in the rotation of said drum.

4. Delivery cabinet as claimed in claim 1, including locking means comprising a bolt carried by said drum and a detent on the bottom of said casing, a spring normally holding said bolt out of the path of said detent, and weight responsive means within said drum positioned to be engaged by a milk bottle in upright position for depressing said bolt into the path of said detent whereby said door is locked when it reaches its closed position through the rotation of said drum, said weight responsive means being shaped to remain unengaged by a milk bottle placed in said drum in inverted position.

5. Delivery cabinet for milk bottles comprising a casing having inner and outer openings on opposite sides and adapted to be set in an aperture in a door in a plane intermediate said openings, a rotatable drum in said casing having an opening in one side registrable with either of said openings in said casing, a door co-operating with the outer casing, a cable connection between said door and drum and windable upon the latter for closing said door through rotation of said drum to a position with its opening in registry with the inner opening of said casing, and a spring for rotating said drum, normally biasing said door to its closed position.

6. Delivery cabinet for milk bottles comprising

5 a casing having inner and outer openings on opposite sides and adapted to be set in an aperture in a door in a plane intermediate said openings, a drum in said casing rotatable upon upper and lower spindles, and having an opening in one side
10 registrable with either of the openings in said casing, a door co-operating with the outer opening, a cable connection between said door and drum and windable upon the latter for closing said door through rotation of said drum to a position with its opening in registry with the inner opening of said casing, and a spring surrounding the lower spindle and connected to said drum and casing for rotating said drum, normally biasing said door to its closed position.
15 7. Delivery cabinet as claimed in claim 1, including locking means comprising a bolt carried by said drum and a resilient detent on the bottom of said casing, a spring normally holding said bolt out of the path of said detent, and weight responsive means within said drum positioned to be engaged by a milk bottle in upright position for depressing said bolt into the path of said detent whereby said bolt in the course of rotation
20 of said drum rides over said detent and is locked
25

thereby against return movement, thereby said door is locked in its closed position, said weight responsive means being shaped to remain unengaged by a milk bottle placed in said drum in inverted position.

8. Delivery cabinet for milk bottles comprising a casing having inner and outer openings on opposite sides and adapted to be set in an aperture in a door in a plane intermediate said openings, a rotatable drum in said casing having an opening in one side registrable with either of said openings in said casing, a door co-operating with the outer casing, a connection between said door and drum closing said door through rotation of said drum to a position with its opening in registry with the inner opening of said casing, a spring for rotating said drum, normally biasing said door to its closed position, and locking means within said drum responsive to the weight of a milk bottle placed uprightly in said drum for locking said door when it is closed, but non-responsive to a milk bottle placed in inverted position in said cabinet, whereby said door remains unlocked.
